ELECTRIC CIRCUIT BREAKER

Charles Bresson, Villeurbanne, France, assignor
to Ateliers de Constructions Electriques de
Delle, Paris, France

Application February 18, 1935, Serial No. 7,138
In Germany February 20, 1934

14 Claims. (Cl. 200—150)

Electric circuit-breakers are known in which a portion of the arc is drawn out in the interior of an extinguishing chamber containing a liquid, whilst another portion of the arc is drawn out outside said chamber. In circuit-breakers of this type, the liquid contents of the extinguishing chamber, partially decomposed and subjected to pressure by the arc, are projected against that portion of the arc which is developed outside the 10 extinguishing chamber.

In some of these circuit-breakers, the fixed contact is disposed in the interior of the extinguishing chamber, and in others it is situated outside this same chamber. On opening the circuit, the movable contact traverses the chamber axially and emerges completely from same at the end of the circuit opening operation.

When high tension current is to be interrupted, the displacement of the movable contact 20 becomes so important that a considerable portion of the arc is developed outside the extinguishing chamber, either on one side or on both sides of same. In such a case the arc is free and by a lateral displacement from its normal situation 25 in the axis of the chamber it consequently frequently escapes the extinguishing action of the blast. The length of the arc is thus unnecessarily increased and this in turn augments the voltage of the arc and results in an important dissipation 30 of energy which is detrimental to the satisfactory operation of the apparatus.

The present invention avoids these disadvantages by maintaining the arc in the axis of the apparatus. It consists in providing the vessel 35 filled with liquid forming part of circuit-breakers of the above referred to type with one or a plurality of guiding devices surrounding the arc developed outside the extinguishing chamber along at least a portion of its length, these guiding 40 devices being separated from the extinguishing chamber and between themselves by spaces filled with liquid, such spaces communicating laterally with the peripheral layers of the liquid in the vessel surrounding the extinguishing chamber 45 and the guiding devices.

The guiding devices may be constituted by rings, annular crowns or nozzles disposed concentrically with respect to the axis of the extinguishing chamber, and their interior diameters 50 will preferably be smaller than the maximum interior diameter of the extinguishing chamber.

These guiding devices may be located between the extinguishing chamber and the fixed contact situated outside said chamber or between 55 said chamber and the movable contact in its open position, or again in both of these locations.

The use of such guiding devices is advantageous in all circuit-breakers in which the height of the extinguishing chamber is smaller than the 60 maximum separation of the two contacts, and

this particularly so in that class of circuit-breakers in which the blowing effect of the extinguishing chamber is reinforced by a supplementary blowing effect independent from that created by the action of the arc on the liquid contained in said chamber. 5

Figs. 1 and 2 of the annexed drawing show diagrammatically and by way of example two embodiments of the invention as applied to a circuit breaker of the last referred to type. 10

In Fig. 1 of the annexed drawing, the vessel 1 of the circuit-breaker is filled with the liquid 2. In the axis of said vessel 1 is disposed the extinguishing chamber 3 provided with an upper nozzle 4 and a lower nozzle 5. On either side of chamber 3 and in the axis of same are disposed the fixed contact 6 and the movable contact 7, this latter being shown in its position of maximum opening. The movable contact 7 is constituted by a tube in the interior of which is disposed a fixed piston 8, these two members constituting a supplementary blowing device which during the separation of the contacts injects a blast of liquid around the arc and through the extinguishing chamber 3. 20

Between the lower nozzle 5 of chamber 3 and the fixed contact 6 are provided two guiding rings 9 and 10 disposed concentrically about the central axis of the apparatus. These rings are fixed to the interior of a support having the form of a tube 12 constituting a prolongation of the lateral walls of chamber 3. Said rings are separated between themselves, from chamber 3 and from the fixed contact 6 by spaces in lateral communication with the peripheral layers 13 of the liquid 2 surrounding chamber 3 through a plurality of apertures 11 of large area provided in tube 12. Said tube 12 constituting a connecting means between members 3, 9 and 10 can be replaced by any other connecting means provided that such connecting means will not hinder the easy communication of the spaces separating members 3, 9 and 10 with the outside liquid. This point is important as the pressure created by the arc in these spaces must be prevented from 30 attaining a value comparable with that produced in the interior of extinguishing chamber 3. 35

The operation of the circuit-breaker is as follows: At the beginning of the separation of contacts 6 and 7 and before the penetration of lower extremity of contact 7 inside extinguishing chamber 3, the arc is drawn out through guiding rings 9 and 10. By reason of the presence of the large apertures 11 this arc is unable to create an appreciable pressure under extinguishing chamber 3 during the second stage of the opening of the circuit-breaker when contact 7 penetrates inside said chamber. At this instant and until the end of the displacement of contact 7, the contents of extinguishing chamber 3 are projected 40 45 50 55 60

against the external portions of the arc. This extinguishing blast is reinforced by the action of the additional injection device constituted by tube 7 and piston 8; this additional injection can take place either from the very beginning of the separation of the contacts or only during the said second stage simultaneously with the extinguishing action of chamber 3. Although an appreciable portion of the arc is thus developed outside chamber 3, between nozzle 5 and contact 6, this arc closely surrounded by rings 9 and 10 is unable to depart from the central zone of tube 12.

Evidently rings 9 and 10 are made from insulating material or are insulated from the contacts of the circuit-breaker.

In accordance with the greater or smaller distance separating the lower nozzle 5 of chamber 3 from contact 6, a simple guiding ring or a plurality of guiding rings may be employed.

On the other hand, in the event of the lowering of the situation of the extinguishing chamber 3, rings of this type or other similar guiding devices could also be provided or even be exclusively provided between the upper nozzle 4 and the extreme open position of movable contact 7.

The circuit-breaker shown in Fig. 2 differs from that just described in that it is designed for lower voltage circuits, the maximum separation of contacts 6 and 7 being smaller. The distance between the lower nozzle 5 of extinguishing chamber 3 and the outside fixed contact 6 being consequently reduced, the free portion of the arc traversing this space is correspondingly shorter. In this embodiment, in order to maintain this portion of the arc along the axis of the circuit-breaker, it is merely necessary to extend in downward direction the lateral walls of extinguishing chamber 3 towards the base by means of a perforated cylinder 12, as shown in Fig. 2. The diameter of this cylinder may be equal to that of extinguishing chamber 3, as shown in the drawing, or it may on the other hand be smaller.

Having now particularly described and ascertained the nature of my said invention and in what manner the same is to be performed, I declare that what I claim is:

1. An electric circuit-breaker comprising, in combination, a vessel containing liquid; an arc extinguishing chamber having aligned openings, one at either end; a fixed contact exterior to and spaced from one end of said chamber; a cooperating contact movable toward and from said fixed contact in alignment with said openings to draw an arc through said chamber; arc guiding means between said fixed contact and said chamber, said guiding means being spaced from the axis of said openings a distance not greater than the distance from said axis to the inner wall of said chamber; and supporting means to support said chamber and said arc guiding means in their relative positions within said vessel, said chamber and said guiding means being submerged in said liquid, and said supporting means adjacent said guiding means being provided with ports for free passage of said liquid.

2. An electric circuit-breaker, comprising in combination, a vessel containing liquid; an arc extinguishing chamber having aligned openings, one at either end; a fixed contact exterior to and spaced from one end of said chamber; a cooperating contact movable toward and from said fixed contact in alignment with said openings, to draw an arc through said chamber; and arc guiding means between said fixed contact and said chamber and spaced from the axis of said

openings a distance not greater than that from said axis to the inner wall of said chamber, said guiding means and said chamber being submerged in said liquid.

3. An electric circuit-breaker comprising, in combination, a vessel containing liquid, an arc extinguishing chamber having aligned openings, one at either end; a fixed contact exterior to and spaced from one end of said chamber; a cooperating contact movable toward and from said fixed contact in alignment with said openings, to draw an arc through said chamber; and arc guiding means comprising at least one annular member of electrically non-conductive material surrounding the axis of said openings between said fixed contact and said chamber, the diameter of said annular member being not greater than the diameter of said chamber, said guiding means and said chamber being submerged in said liquid.

4. An electric circuit-breaker comprising, in combination, a vessel containing liquid; an arc extinguishing chamber having aligned openings, one at either end; a fixed contact, a cooperating contact movable toward and from said fixed contact in alignment with said openings, to draw an arc through said chamber, said fixed contact being exterior to and spaced from one end of said chamber a distance greater than the length of the path of said movable contact within said chamber; and arc guiding means between said fixed contact and said chamber and spaced from the axis of said openings a distance not greater than that from said axis to the inner wall of said chamber, said guiding means and said chamber being submerged in said liquid.

5. An electric circuit-breaker comprising, in combination, a vessel containing liquid; an arc extinguishing chamber having aligned openings, one at either end; a fixed contact exterior to and spaced from one end of said chamber; a cooperating contact movable toward and from said fixed contact in alignment with said openings, to draw an arc through said chamber; and arc guiding means comprising an annular member of electrically non-conductive material surrounding the axis of said openings between said fixed contact and said chamber, said guiding means and said chamber being submerged in said liquid.

6. An electric circuit-breaker comprising, in combination, a vessel containing liquid; an arc extinguishing chamber having aligned openings, one at either end; a fixed contact exterior to and spaced from one end of said chamber; a cooperating contact movable toward and from said fixed contact in alignment with said openings, to draw an arc through said chamber; arc guiding means comprising at least one annular member of electrically non-conductive material surrounding the axis of said openings between said fixed contact and said chamber, the diameter of said annular member being no greater than the diameter of said chamber; and supporting means to support said chamber and said arc guiding means in their relative positions within said vessel, said chamber and said guiding means being submerged in said liquid, and said supporting means adjacent said guiding means being provided with ports for free passage of said liquid.

7. An electric circuit-breaker comprising, in combination, a vessel containing liquid; an arc extinguishing chamber having aligned openings, one at either end; two contacts, the one fixed and the other movable in alignment with said

openings to draw an arc through said chamber; and arc guiding means spaced from the path followed by said movable contact exterior to one end of said chamber in drawing an arc through 5 the latter, the distance separating said guiding means from said path being not greater than the distance of the wall of said chamber from said path, said chamber and said guiding means being submerged in said liquid.

10 8. An electric circuit-breaker comprising, in combination, a vessel containing liquid; an arc extinguishing chamber having aligned openings, one at either end; two contacts, the one fixed and the other movable in alignment with said 15 openings to draw an arc through said chamber; and arc guiding means spaced from the path followed by said movable contact exterior to one end of said chamber in drawing an arc through said chamber the distance separating said guiding means from said path being not greater than the distance of the wall of said chamber from said path; and supporting means to support said 20 chamber and said guiding means within said vessel, said chamber and said guiding means being submerged in said liquid.

9. An electric circuit-breaker comprising, in combination, a vessel containing liquid; an arc extinguishing chamber having aligned openings, one at either end; two contacts, the one fixed 30 and the other movable in alignment with said openings to draw an arc through said chamber; and arc guiding means comprising at least one annular member of electrically non-conductive material surrounding the path followed by said 35 movable contact exterior to said chamber in drawing an arc through the latter, the diameter of said annular member being no greater than the diameter of said chamber, said guiding means and said chamber being submerged in said liquid.

40 10. An electric circuit-breaker comprising, in combination, a vessel containing liquid; an arc extinguishing chamber having aligned openings, one at either end; two contacts, the one fixed and the other movable in alignment with said 45 openings to draw an arc through said chamber; and arc guiding means comprising an annular member of electrically non-conductive material surrounding the path followed by said movable contact exterior to said chamber in drawing an 50 arc through the latter, said guiding means and said chamber being submerged in said liquid.

11. An electric circuit-breaker comprising, in combination, a vessel containing liquid; an arc extinguishing chamber having aligned openings, 55 one at either end; two contacts, the one fixed and

the other movable in alignment with said openings to draw an arc through said chamber; arc guiding means comprising at least one annular member of electrically non-conductive material surrounding the path followed by said movable contact exterior to said chamber in drawing an 5 arc through the latter, the diameter of said annular member being no greater than the diameter of said chamber; and supporting means to support said chamber and said guiding means in 10 their relative positions within said vessel, said guiding means and said chamber being submerged in said liquid, and said supporting means adjacent said guiding means being provided with ports for free passage of said liquid. 15

12. An electric circuit breaker comprising, in combination, a vessel containing liquid; an arc extinguishing chamber having aligned openings, one at either end; two contacts, the one fixed and the other movable in alignment with said 20 openings to draw an arc through said chamber, the length of the path traversed by said movable contact exterior to one end of said chamber being longer than its path within said chamber; and arc guiding means spaced from said path exterior 25 to said chamber a distance no greater than the distance of the wall of said chamber from said path, said chamber and said guiding means being submerged in said liquid.

13. An electric circuit-breaker comprising, in 30 combination, a vessel containing liquid; an arc extinguishing chamber having aligned openings, one at either end; two contacts, the one fixed and spaced from one end of said chamber, and the other movable in alignment with said openings 35 to draw an arc through said chamber, the walls of said chamber being extended at one end about the space separating said fixed contact from that end of said chamber; said chamber and said extended walls thereof being submerged in said 40 liquid and said extended walls being provided with ports for the free passage of said liquid.

14. An electric circuit-breaker comprising, in combination, a vessel containing liquid; an arc extinguishing chamber having aligned openings, one at each end; two contacts, the one fixed and the other movable in alignment with said 45 openings to draw an arc through said chamber, the walls of said chamber being extended at one end about the path traversed by said movable contact exterior to said chamber, said chamber and said extended walls being submerged in said liquid and said extended walls being provided with ports for the free passage of said liquid. 50
